UNITED STATES PATENT OFFICE.

LAMAR LYNDON, OF NEW YORK, N. Y.

WATER-WHEEL GATE.

Application filed October 4, 1921. Serial No. 505,419.

To all whom it may concern:

Be it known that I, LAMAR LYNDON, a citizen of the United States, and resident of New York, in the county and State of New York, have invented certain new and useful Improvements in Water-Wheel Gates, of which the following is a specification.

My invention relates to improvements in the construction of the so called "wicket gates" for water wheels.

It is well known that, unless the wicket gates are all machined at the inner points and the surfaces where contact is made between adjacent gates are prepared so thoroughly as to secure a perfect contact, and, further, the operating mechanism comprising the connecting links and pivots is made with great accuracy, there will be no uniform and complete shutting off of the water flow, which should be the case when the gates are closed. If one gate point is slightly longer than that of some other gate, or if the thickness of all of the gates is not exactly the same, such longer, or thicker, gates will make contact before all other gates around the periphery of the water wheel can close, and no further movement of the operating mechanism can take place

because the mechanical limit of motion will have been reached. On the other hand, the machining of each gate and accurate adjustments of the various operating parts of the mechanism form a too costly operation and, in ordinary, commercial types of water wheels the use of such means is not even considered. As a result, a great lack of operating efficiency is prevailing in practice, it being customary to place the gates

in position, work the shifting ring until various high spots of the gate bodies and extra long points of various other gates have been located, then chip and file the gates until some semblance to complete closure of all the gates is effected. As a matter of fact, however, this process of adjusting inequalities in the gates being far from satisfactory, there is always a considerable leakage through the wicket gates

as they are made today, which results in a continuous loss of water through water wheels which are delivering no power, i. e. when the gates are supposedly tightly closed. Furthermore, this leakage flow is usually great enough to keep a water wheel, which is attached to an electric generator,

continuously in motion, even after gate closure, and, in such a case, it becomes necessary to provide some extraneous means for bringing the water wheel, and its attached generator to rest. In some instances, mechanical brakes have been used for this purpose, in other cases, generator fields are fully excited, so that induced eddy currents will act as an electro-magnetic brake and finally stop the rotation of the unit.

My invention is designed to eliminate all chipping and filing, all adjustment of the various parts of the operating mechanism, and applies to any type of wicket gate. An important feature of my invention is that it not only eliminates the necessity for such mechanical and adjusting operations, but, at the same time, eliminates all water losses as well as the need of extraneous apparatus for bringing to rest units that have been taken out of service. Other useful features of my invention will be made apparent from the detailed description thereof.

Referring to the accompanying drawings: 80

Figure 1 is a section of a standard water wheel, showing the arrangement of wicket gates and the operating mechanism thereof.

Figure 2 is a detail view of two adjacent wicket gates.

Referring particularly to Figure 1, wherein the full lines indicate the general arrangement of the parts when the wicket gates are closed, and the dotted lines, when these gates are open, 1 is a section of the water wheel casing, 2 is one of the wicket gates, mounted therein on a pivot 3, the ends of the gates being attached to the shift ring 4 by means of links, of which 5 is the one corresponding to the gate 2. The gates are provided with deflectors, such as 6, to give proper direction to the flow of water. A connecting or shift rod 7 serves to move the shift ring 4 and thereby open or close the gates. The gates are made of cast iron, steel, or other suitable metal. Approximately along the line where the point of one gate makes contact with the adjacent gate, at closure, the metal in the body of the gate is grooved out through the entire width of the gate and the space thus formed is then filled with some soft material, such as babbitt metal, as indicated at 8 on Figure 1 and, by the same notation, in the detail Figure 2. The inserted soft metal or other soft material capable of resisting the action of water has just enough plasticity to allow

the gate point to cut into it and make a tight contact between two consecutive gates.

When the water wheel is assembled, it only becomes necessary to close the gates as tightly as possible, and then strike with a hammer or mallet those of the gate points which make contact with adjacent gates before contact is made and closure effected all around the periphery of the wheel, the hammering of such gate points and the slight, but sufficient, plasticity of the soft material under them allowing other gates to close, this simple operation being continued until all the gates are tightly closed. This condition of tight closure will be attained even if the so called gate point by which is meant the thinner end of the gate, is not truly straight from one edge to the other of the gate.

While the soft material inserted in the gate body is preferably some metal, such as lead or babbitt, I do not limit my invention to soft metals, any material which fulfills the conditions of permitting a gate point to be driven into it without injury to the gate and which will withstand the action of the water flow, being obviously within the scope of my invention. For instance, certain kinds of wood, if driven into dove tail formed slots made in the gate body, would meet the requirements. Nor does my invention preclude other ways of driving the gate points into the soft material than hammering, since the same result would be ob-

tained by cutting out of the inserted soft material enough to form a seat for receiving the adjacent gate point.

Having fully described my invention, I claim:

1. A wicket gate for water wheels, made of a comparatively hard material and provided with a strip of softer material, which strip is inset in a portion of said wicket gate and forms the seat for one end of the next adjacent gate cooperating therewith. 45

2. A wicket gate for water wheels, having a portion made of a material capable of resisting the action of the flow of water and of sufficient plasticity to allow the surface of said portion to become slightly depressed under impact. 50

3. A wicket gate for water wheels, made of comparatively hard material and having a strip of softer material inset therein, said inset material being of sufficient plasticity to permit the harder material of an adjacent gate to be forced into the softer strip. 55

4. In a water wheel, wicket gates, each gate having a strip of comparatively soft material inset therein and of sufficient plasticity to allow the tightening of contact between consecutive gates all around the periphery of said water wheel by forcing gate ends into said strips of soft material. 60
